UNITED STATES PATENT OFFICE.

CHARLES H. IRWIN, FRANCIS I. HOEFLER, AND JAMES W. SIMMONS, OF WILMINGTON, OHIO; SAID HOEFLER AND SIMMONS ASSIGNORS TO SAID IRWIN.

AUGER-BIT DIE.

SPECIFICATION forming part of Letters Patent No. 412,957, dated October 15, 1889.

Application filed August 27, 1889. Serial No. 322,140. (No model.)

To all whom it may concern:

Be it known that we, CHARLES H. IRWIN, FRANCIS I. HOEFLER, and JAMES W. SIMMONS, all of Wilmington, in the county of Clinton 5 and State of Ohio, have invented new and Improved Auger-Bit Dies, of which the following is a full, clear, and exact description.

Our invention relates to dies for forging auger-bits, and has for its object to provide 10 series of dies of this character to be operated successively for forging bits having a spiral blade or flange which surrounds a central stem which has a spiral form between the convolutions of the blade and gradually 15 merges into them. The dies also produce on the bit-stem within the last or point-approaching convolution of the main spiral blade or flange, which carries one cutter, an auxiliary semi-spiral flange, which carries the other 20 cutter. Auger-bits made by these dies are easily finished, are very strong, and easily clear themselves of chips made by the cutters.

The invention consists in certain novel features of construction of the auger-bit dies, all 25 as hereinafter described and claimed.

Reference is to be had to the accompanying drawings, forming a part of this specification, in which similar letters of reference indicate 30 corresponding parts in all the figures.

Figures 1 and 2 are face views of opposing dies adapted to form the spiral body portion of an auger-bit shown in Fig. 5 of the drawings. Figs. 3 and 4 are face views of opposing dies adapted to form the cutters and gimlet-point stud of the bit-blank shown in Fig. 6 of the drawings. Figs. 7 and 8 are face views of opposing dies adapted to forge the head or point of the straight center-stem-bit 35 blank shown in Fig. 11 of the drawings. Figs. 9 and 10 are face views of opposing dies adapted to forge the head or point of a bit-blank of the same diameter as that shown in Fig. 11, but having a spiral center stem. Fig. 40 12 shows part of a bit-blank produced with a spiral center stem forged in the dies shown in Figs. 1 and 2 and ready for action of the dies forming the auxiliary spiral blade or flange, the cutters, and the gimlet-point stud 45 or blank. Figs. 13 and 14 are face views of

opposing dies adapted for partly forging the head of the straight center-stem-bit blank shown in Fig. 17 to give it the form shown in Fig. 18 of the drawings, and Figs. 15 and 16 are face views of opposing dies which forge 55 the extremity of the bit-blank first struck up in the dies shown in Figs. 1 and 2 of the drawings.

The invention refers more particularly to dies for forging a bit having a spiral blade or 60 flange which surrounds a central stem which has a spiral form between the convolutions of the blade or flange and gradually merges into them and presents lengthwise of the finished bit a laterally zigzag or wavy line to the eye 65 however the bit may be viewed. The dies for forging the cutting-head of such a bit also form special features of the invention.

Figs. 1 and 2 of the drawings show opposing dies adapted for forging the body or spiral-bladed portion of a bit of this character. I show these two dies each provided with but one peculiarly-formed cavity or combination of recesses, but each die may also have a primary shallower cavity or combination of recesses providing for first "breaking down" 70 therein a metal rod prior to completing the bit-body forging in the opposing die cavities or recesses shown. One die A is formed with two diagonally-ranging concaved or semicircular cavities *a a*, and the other die A' is provided with but one such cavity *a'*, which, when the dies are face to face, comes between the two concavities *a a* of the other die. The die A', each way beyond its diagonal concavity 75 *a'*, is provided with a semi-spirally formed lengthwise depression *b'*, and beyond these two depressions *b'* the die is preferably provided with concaved depressions *c' c'*. The other die A is provided between its two di- 80 agonals concavities *a a* with a semi-spirally formed lengthwise depression *b*, and beyond or at the outer walls of the two concavities *a a* are formed partial spiral lengthwise de- 85 pressions *c c*, and at one end is formed a de- 90 pression *d*, which corresponds in shape with one end portion of the diagonal concavities *a a* at the same side of the die. The de- 95 pressions *c b b' b'* are peculiarly formed. They do not take a general course parallel

longitudinal line $x-x$, which would bisect the center of the die concavities or depressions in the line of the axis of a bit forged by the dies, but they range diagonally and preferably at a very quick pitch, and are made comparatively shallow at their center portions and gradually deepen and broaden toward their ends, which merge by rounding or curved lines into the sides of the diagonal concavities $a a'$ of the dies and make these concavities wider at the meeting faces of the dies than at their bases. It is obvious from Figs. 1 and 2 of the drawings that the diagonal flange-forming concavity a' of the die A' opposes the central spiral stem-forming depression b of the die A , and that the two diagonal flange-forming concavities $a a$ of the die A oppose the two spiral stem-forming depressions $b' b'$ of the die A' . With dies thus formed and working one toward the other a heated rod placed between them and gradually turned by the operator will be forged into a bit-body having substantially the form shown in Fig. 5 of the drawings and provided with the spiral or convoluted stem e , formed mainly in or by the die-depressions $c b' b$, and a spiral flange f , surrounding this stem and produced mainly in or by the die-concavities $a a'$. It may, however, be more correct to state that the concavities and depressions of both dies co-operate to produce a bit-body having a spiral blade or flange which surrounds a central stem which has a spiral form between the convolutions of the blade or flange and gradually merges into them and presents lengthwise of the bit a wavy line to the eye from any lateral point of view, and greatly facilitates clearance of chips from a hole bored by the finished bit. The depressions $c' c' d$ provide for feeding the metal rod properly to the dies, and the two opposing depressions $c' d'$ leave sufficient stock e' at the outer end of the rod to form thereon by other dies, hereinafter referred to, the short auxiliary spirally-disposed flange f' , at the extremity of which one cutter is formed, while the opposite cutter is forged at the extremity of the main spiral blade or flange f of the bit-body.

Fig. 12 of the drawings shows a portion of the bit body or blank after it has been operated on by these dies $A A'$ to form the spiral blade and center stem and leave stock e' at the end of the rod from which to forge the short spiral flange and cutters above mentioned.

Figs. 15 and 16 of the drawings show the dies $B B'$, by which the partly-forged bit blank or body shown in Fig. 12 is broken down at the end e' to form on the bit-stem the short auxiliary flange f' by the smaller and larger concavities or depressions $b^2 b^3$, formed in the dies $B B'$, respectively, while the bit-body is held in position by the concavities $a a' a'$ and depressions $b' b' c' c'$, which are like those bearing the same reference-letters in the dies $A A'$, hereinbefore described. In other words, these two dies $B B'$

form at or from the end e' of the bit-blank shown in Fig. 12 the flange f' and an end stud e^2 substantially like the flange and stud 70 shown on the bit-blank in Fig. 18 of the drawings. This last-named bit-blank, however, has a straight center stem e^3 , which the spiral blade f surrounds, and on which the auxiliary flange f' is forged. This end stud e^2 75 when formed on a bit-blank having a spiral center stem e and forged in the dies $B B'$ will be produced mainly by the central depression b^4 in one of the dies.

The two dies $C C'$ (shown in Figs. 9 and 10 80 of the drawings) are used to produce the cutters $g g'$ and gimlet-point stud g^2 after the bit blank or body has been acted on by the dies $B B'$ to form the flange f' and the stud e^2 . Depressions $d' d'$ and $d^2 d^3 d^4$ in the dies 85 $C C'$ form the cutters $g g'$ and gimlet-point stud g^2 at the head of a bit having the spiral or convoluted center stem e above described.

Figs. 3 and 4 of the drawings show a pair of dies $D D'$, adapted to form the cutters $g g'$, and gimlet-point stud g^2 on the end of a bit-blank of larger diameter than is shown in Figs. 5 and 12, but of the same style or with a spiral center stem e . In this case the short auxiliary spirally-disposed flange or blade f' 95 is produced by the depression h in the die D , while the depression h' in the die D' produces the lower convolution of the main spiral blade f of the bit. Depressions $h^3 h^4$ in the two dies produce the cutters $g g'$ of the 100 bit, and when a lower spur-cutter g^3 is to be produced on the cutters, as indicated in dotted lines in Fig. 6 of the drawings, lower depressions $h^5 h^6$ will be produced in the dies $D D'$ next the depressions $h^3 h^4$, as also indicated in dotted lines. Depressions h^6 in the two dies form the gimlet-point stud g^2 of this bit-blank.

Figs. 13 and 14 of the drawings show opposing dies $E E'$, adapted to break down the 110 extremity e' of the straight-stem-bit blank shown in Fig. 17 to form the short auxiliary spirally-disposed flange f' around the stem and partially form the bit-cutters, this spiral flange being produced by the depressions $i i'$ 115 in the dies, while the main spiral flange f is formed by the depressions i^2 . The straight stem e^3 is produced by the depressions i^3 , and the gimlet-point-stud blank e^2 is formed mainly by the depression i^4 in one of the dies. 120

Figs. 7 and 8 of the drawings show a pair of dies $F F'$ having depressions $k k'$, by which are produced on the bit-blank shown in Fig. 18 the cutters $g g'$ and gimlet-point stud g^2 shown on the bit-blank represented 125 in Fig. 11 of the drawings. The straight center stem of this bit is formed by the depressions $k^2 k^3$ of these two dies, while the main spiral blade or flange f is produced by the depressions k^3 , and the auxiliary spiral flange 130 f' is produced by the depressions k^4 , as will readily be understood from the aforesaid description.

It is manifest that our invention is not lim-

ited to the construction of the first above-described dies, by which the peculiar bit-blank body E shown in Figs. 5 and 12 of the drawings is formed, as this body is not of itself a completely-forged bit-blank; hence our invention also includes the dies herein described for producing the auxiliary cutter-carrying flange f', the cutter-blanks g g', and gimlet-point-stud blank g², and especially 10 when these are formed on a bit-body blank E, having the convoluted center stem e. We consider the herein-described series of dies operating one pair after the other are legitimately in combination to produce by their successive but joint actions completely-forged bit-blanks, lacking only the ordinary or any approved tempering and polishing operations 15 to fit them for use as completely-finished easy-working auger-bits.

20 Having thus described our invention, what we claim as new, and desire to secure by Letters Patent, is—

1. In dies for forging auger-bits, the bit-body dies made with adjacent inclined spiral-blade-forming concavities, and with contiguous diagonally-ranging semi-spiral center-stem-forming depressions made shallow at their center parts and gradually deeper and broader toward their ends, which merge into 25 the spiral-blade-forming concavities, substantially as described, whereby the dies will produce a bit-body having a spiral blade or flange surrounding a central stem, which itself has a spiral form between the convolutions of said blade or flange, as set forth.

2. In dies for forging auger-bits, the bit-heading dies provided with concavities and depressions receiving the outer parts of the central stem of the blank and its surrounding main spiral blade or flange, and provided, also, with semi-spiral flange-forming depressions at or between the concavities and depressions producing the last convolution of the main spiral flange of the bit, substantially 45 as described, whereby the bit-blank will have support at its outer part in the die while an auxiliary semi-spiral flange is produced on it by the dies within the last convolution of the main spiral flange of the bit, as set forth.

50 3. In dies for forging auger-bits, the bit-head-forming dies provided with concavities and depressions receiving the outer parts of the center stem of the bit-blank and its surrounding main spiral blade or flange, and provided, also, with semi-spiral-flange-forming 55 depressions at or between the concavities or depressions forming the last convolution of the main spiral flange of the bit, and provided,

also, with an extension of the center-stem-forming depressions beyond those forming the main and auxiliary spiral flanges, substantially as described, whereby the bit-blank will have support at its outer part in the dies while an auxiliary semi-spiral flange and a central gimlet-point-stud blank is produced 60 on it by the dies, as set forth.

4. In dies for forging auger-bits, the bit-point and cutter-forming dies provided with concavities and depressions receiving the outer parts of the central stem of the blank 70 and its surrounding main spiral blade or flange, and also receiving the auxiliary semi-spiral flange formed within the last convolution of the main spiral flange, and provided, also, with depressions producing cutting-edges 75 at the extremities of the main and auxiliary flanges, and provided, also, with depressions forming from the projecting end of the center stem the tapering gimlet-point stud of the bit, substantially as herein set forth. 80

5. In dies for forging auger-bits, the bit-body dies A A', formed with adjacent inclined spiral-blade-forming concavities a a' a', contiguous diagonally-ranging semi-spiral center-stem-forming depressions b c b', which 85 are shallow at their center parts and gradually deepen and broaden toward their ends, which merge into the spiral-blade-forming concavities and end depressions c' c' d, substantially as described, for the purposes set 90 forth.

6. In dies for forging auger-bits, the heading-dies B B', provided with inclined spiral-blade and center-stem receiving depressions a a' b b', and provided, also, with depressions b² b³, forming on a bit-blank an auxiliary cutter-supporting flange within the last convolution of the main spiral blade or flange, and provided, also, with a depression b⁴, forming the gimlet-point-stud blank, substantially 100 as herein set forth.

7. In dies for forging auger-bits, the bit-pointing dies C C', formed with concavities a a' a', depressions b c b' b² b³, receiving the main spiral blade, the center stem, and the 105 auxiliary flange of the bit, and provided, also, with gimlet-point-forming depressions d' d' and cutter-forming depressions d² d² d², substantially as herein set forth.
